(57) **CLAIM**

The ornamental design for a desk, as shown and described.

DESCRIPTION

FIG. 1 is a front perspective view of a desk embodying our design;

FIG. 2 is a front elevational view of the desk shown in FIG. 1;

FIG. 3 is an elevational view of the left side of the desk shown in FIG. 1;

FIG. 4 is an elevational view of the right side of the desk shown in FIG. 1; and,

FIG. 5 is a top plan view of the desk shown in FIG. 1. In FIGS. 1-5, broken lines showing structure are for illustrative purposes only and form no part of the claimed design.

1 Claim, 5 Drawing Sheets
